UNITED STATES PATENT OFFICE.

THEODORE E. SILVERA, OF PHILADELPHIA, PENNSYLVANIA.

HAIR-RESTORER.

1,378,731.

Specification of Letters Patent.

Patented May 17, 1921.

No Drawing.

Application filed August 14, 1920. Serial No. 403,505.

To all whom it may concern:

Be it known that I, THEODORE E. SILVERA, a citizen of the United States, residing at 808 Mountain street, Philadelphia, in the 5 county of Philadelphia and State of Pennsylvania, have invented a certain new and useful Hair-Restorer, of which the following is a specification.

My invention relates to hair restorers and 10 has for its main purpose to make cocoanut oil available, improving its quality for the purpose and securing a restorer of a simple composition, to manufacture at a low cost, free from dangerous ingredients.

15 Further purposes will appear in the specification and in the claims.

My invention relates to the methods of manufacture as well as the products secured.

20 Though I have preferred to illustrate my invention by but one method of manufacture, I have recognized that changes therefrom may be made in various particulars as will be obvious to those skilled in the 25 art and without departing from the spirit and scope of my claims.

I make my hair restorer from the meat of the cocoanut, preferring to reject the liquor of the nut and to select well dried nuts and 30 to avoid those which are "strong" or in the least rancid.

In order to facilitate the extraction of the oil from the meat, I grind the latter up and wash it with hot water. The exact temperature of the water is not material, good 35 results being obtainable throughout a wide range. I use water at a temperature of about 180° F.

The combined cocoanut oil and water 40 thus obtained is drained off and strained through cloth.

As the water is heavier than the oil it settles to the bottom having the oil floating upon the surface of the water.

45 In the subsequent separation of the oil from the water the natural and obvious way would be either to decant the lighter oil from the heavier water before cooling or to allow the fluids to cool and remove the 50 rather viscous oil from the surface. In either event the product would be greatly inferior for my purposes and incapable of producing the results secured by me.

55 I find that the product is very much improved for hair restoring purposes by heating the oil to the temperature approximately

of boiling water and maintaining it at this temperature while the fatty acids are liberated in whole or in part and while the constituents having low vaporizing points are 60 driven off.

The simplest, most convenient, reliable and in every way the best method of accomplishing this which I have found has been by boiling out the water from beneath 65 the oil; which maintains the temperature for a time which may be very nicely gaged, stirs the oil by the bubbling of the steam through it and in proportion to the quantity of water present and the condition of the 70 fire, treats the oil by these bubbles at a temperature suitable for combination of the steam with the oil to change the character of the oil, hydrolyzing it, liberating fatty acids and driving off separable constituents 75 having a low vaporizing point. When the water has been evaporated a decided custard-like precipitate appears which must be strained out.

The resulting product is oily and colorless 80 when at summer temperatures and when cooled a nearly white opaque salve in the form of a paste having a consistency nearly that of vaseline and having a flashing point about six degrees higher than that of the 85 original oil. It still has a distinct cocoanut odor, is so free from injurious matter that it can be eaten without danger, is easily assimilated and has remarkable capacity for invigorating the scalp and causing hair 90 to grow upon uncultivated and seemingly arid scalp areas.

It is quite desirable to avoid burning this product. The easiest way to avoid this is to stop the operation at or very soon after 95 the last water has been evaporated. I use about a pint of hot water for half a dozen cocoanuts but this can evidently be increased within reasonable limits unless it be desired to shorten the process so as not to wholly 100 change the oil. The product is decanted to free first from the greater part of the precipitate.

The decanted liquid is then strained thoroughly, not only to free from any matter 105 in suspension, but to improve the color. Additionally straining within reasonable limits, makes the product much lighter in color than it would be otherwise.

To improve the salability of the product, 110 a few drops of perfume may be put in, the quantity depending upon the judgment of

the maker. I find white rose a very acceptable perfume for the product.

After the product has been made and cooled to a paste, a very desirable shampoo 5 may be prepared from it by mixing a little of the paste with hot water and a small quantity of good soap to give a lather.

Both the salve and the shampoo are advantageous in treating dandruff, softening 10 the dandruff and restoring the healthy condition of the scalp.

Having thus described my invention, what I claim as new and desire to secure by Letters Patent is:—

15 1. A cocoanut oil salve comprising when cooled below summer temperature, a viscous, opaque paste low in oils volatile at the temperature of boiling water.

20 2. A cocoanut oil salve comprising when cooled below summer temperature, a viscous, opaque paste and having the fatty acids liberated.

3. A cocoanut oil salve comprising when cooled below summer temperature, a viscous, opaque paste, having the fatty acids liberated and low in oils volatile at the temperature of boiling water. 25

4. The method of forming a hair restorer, from the heat of the cocoanut which consists in finely dividing the cocoanut meat, treating it with hot water to extract the oil and boiling the water of the product thus obtained through the oil. 30

5. The method of making a hair tonic from the heat of the cocoanut which consists in finely dividing the meat, treating it with hot water, straining the heated mixture of cocoanut oil and water obtained, boiling the water, maintaining the temperature of the product not much above the boiling point of 40 water, decanting the liquor, straining the liquor and allowing to cool. 35

THEODORE E. SILVERA.
